UNITED STATES PATENT OFFICE.

MAX SCHUPPE, OF NEW YORK, N. Y., ASSIGNOR TO BERNARD F. SEADLER,
OF NEW YORK, N. Y.

ELECTRIC-CIRCUIT CONTROLLER.

No. 858,222.

Specification of Letters Patent.

Patented June 25, 1907.

Application filed January 7, 1905. Serial No. 240,091.

To all whom it may concern:

Be it known that I, MAX SCHUPPE, a citizen of the United States, and a resident of the city of New York, county of New York, 5 and State of New York, have invented certain new and useful Improvements in Electric-Circuit Controllers, of which the following is a specification.

My invention relates to electric circuit controllers.

Some of the objects of my invention are to provide such a circuit controller that will prevent all danger from sparking; and also that will prevent a too sudden turning on and off 15 of the full current through the circuit.

Other objects of my invention are to provide means for automatically breaking the circuit through mechanism operated by a motor, and for breaking said circuit gradually.

My invention consists of certain features and details, hereinafter described and shown.

In the drawings—Figure 1 is an elevation of one embodiment of my improved circuit controller, showing diagrammatically the circuit, motor armature and field. Fig. 2 is an end elevation of the controller showing in diagram the connection between the motor and switch. Fig. 3 is a detail of the contact 20 and insulated portions of the controller, as shown in Fig. 1.

Similar characters represent like parts in all the figures.

1 represents an electric motor armature, 35 and 2 its shaft.

3 is a shaft which turns very slowly during the rapid revolutions of the motor shaft 2, and which shaft 3 may be turned with shaft 2 by means of reducing gearing.

40 4 is a lever switch loosely journaled on the shaft 3 and provided at one end with a counterbalance weight 5 for a purpose hereinafter to be described.

6 is a bar provided with vertical slots 7, 45 through which pass pins 8 secured to the machine frame, and providing means by which said bar may be guided vertically on the machine frame. The bar 6 is provided with a pin 9 extending laterally above the lever 50 switch 4, and by means of which said lever switch can be turned on the shaft 3 when the bar 6 drops or is drawn downward, see Fig. 1.

10 is a trip lever fulcrumed above the bar 6 and having its longer arm extending into a

vertical slot 11 in a tube or chute 12. The 55 short arm of the lever 10, that is the arm opposite to that which is in the slot 11, is provided with a counterbalance weight 13, so that the long arm of lever 10 will be held in contact with the upper end of the slot 11, 60 until a weight heavy enough to counterbalance weight 13 drops upon the long arm of lever 10 in said slot. When said weight drops upon said long arm of the lever, it will act to lower the same and drop the lever. 65

14 is a spring latch lever fulcrumed above the bar 6 and below the lever 10, and with the latch of said lever 14 normally engaging with a pin 15 on the bar 6, so as to lock said bar in its raised position and with the arm of 70 the lever 14 opposite its latch extending substantially horizontally under a downward extension 16 of the lever 10, which rests upon said arm or lever 14, (see Fig. 1).

17 is a spring latch lever pivoted to the 75 frame of the machine at a point below the lever 14 and adapted to engage with pin 18 on the lever switch 4 when the arm bearing said pin is in its lowest position, as shown in full lines in Fig. 1. The bar 6 is provided 80 with a laterally extending cam 19 for engaging with the arm of the lever 17 opposite the latch when said bar 6 rises, so as to force said latch away from engagement with the pin 18 to permit the switch 4 to be drawn down by 85 its weight 5, and to assume the position shown in dotted lines in Fig. 1. Secured to the shaft 3 is a disk 20 provided with a lateral pin 21, and the bar 6 is provided with two laterally extending cams or noses 22 and 90 23 for engagement with the pin 21.

24 is a weight suspended by a cord 25 from the lower end of bar 6, to draw said bar down when released from the latch lever 14.

26—26 are two terminals with which 95 switch 4 is to engage and which terminals are in the circuit 27 in which is also the motor field 28. The upper part of each terminal 26 is composed of an insulated section. Upon this part switch 4 rests, as shown in dotted 100 lines in Fig. 1, when the machine is at rest.

29—29 are other terminals with which the switch 4 is adapted to engage, and which terminals are in the circuit 30, in which is also the motor armature 1, the controller 31 and 105 its branch circuits 32. The lower part of each terminal 29 has an insulated section, and upon this switch 4 is adapted to rest

when the machine is not operating, as shown by dotted lines in Fig. 1. Between the terminals 26—26 and 29—29 is insulation 33 (see Figs. 1 and 3), and 34 are contact pins 5 which pass loosely through holes in the switch 4, and are held in yielding contact against the respective terminals by a spring 35 which is secured to the switch 4. In order to insure that the latch 17 should be tripped at the proper time when the bar 6 rises so as to release the pin 18 from the latch 17, I provide a regulating screw 36, which extends through a projection 37 on the cam 19 and to the latch 17. This will enable 15 said screw 36 to be adjusted so as to compensate for any wear that may take place upon the cam 19, and I have also added a lock nut 38 through which the screw 36 passes, to lock said screw in its proper position when adjusted to the same.

As soon as the long arm of the lever 10 is forced down by the proper coin or token in the chute 12, the extension 16 on said lever 10 will trip the latch lever 14 so as to release 25 the pin 15 on the bar 6, when said bar will be drawn down by its weight 24, until the nose or cam 22 rests on pin 21, and the pin 9 on the bar 6 will pull down the adjacent arm of the switch 4, bringing the pins 34 in contact 30 with the two terminals 26 so as to complete the circuit through line 27, and thus energizing the field 28. Immediately thereafter the pins 34 on the opposite arm of lever 4 will make contact with terminals 29, completing 35 the circuit through line 30, the motor armature 1, controller 31 and branch circuits 32, and vitalizing the motor, and thus cause the shaft 3 and the disk 20 to revolve in the direction of the arrow in Fig. 1. This shaft 3 40 will revolve slowly, as before described, as will also of course, the disk 20. The pin 21 on said disk will ride slowly on cam 22 so as to permit the bar 6 to descend slowly, and consequently to prevent a too sudden movement 45 of the lever switch 4, and thereby preventing turning on the full current at once. When said disk has made about three quarters of a revolution, the pin 21 will come into contact with the upper edge of the cam 23, and will 50 then move along the surface thereof until it gets into the recess 39 between said cam and the cam 22, and then bearing upon the upper shoulder of said recess, will force the bar 6 upward; and just as the disk 20 is about to 55 complete one revolution, the pin 21 will cause the bar 6 to rise so that the pin 15 on said bar will arrive at a point a little above the latch 14. A little further movement of the pin 21 on the disk 20 will cause said pin to 60 raise the bar 6 sufficiently to cause the cam 19, or the pin 36 on said bar, to trip the latch 17 and to disengage the latch from pin 18. At this moment, the disk 21 passing out of 65 the recess 39, the bar 6 is allowed to fall so that the pin 15 is caught by the hook on the

latch 14. At the same moment the switch being before liberated by the tripping of the latch 17, the counterweight 5 will throw the switch back into the position shown in dotted lines in Fig. 1, thus breaking the circuit first 70 through the motor armature 1 and then through the field 28. The different parts of the machine that are operated by the motor will thus be stopped and the whole apparatus will be held in the position shown in Fig. 1, 75 with the lever as shown in dotted lines.

It will be seen that by energizing the field before energizing the armature and by deenergizing the armature before deenergizing the field, the circuits will not be too abruptly 80 completed and broken, and all danger from such trouble will be avoided.

It will of course be evident that my improved switch and its connections may be applied to any electric motor, and to any machine or mechanism that is adapted to be operated or controlled by electricity.

My invention in its broader aspects is not limited to the precise construction described and shown, as many changes other than 90 those suggested may be made without departing from the main principles of my invention or sacrificing its chief advantages.

What I claim as new and desire to secure by Letters Patent, is:

1. An electric circuit controller for an electric motor, comprising two branch circuits, one for connection with the motor armature and the other with its field, and means for completing it through the field before completing it through the armature, and for breaking the circuit through the armature before breaking it through the field, and mechanical connections between the motor and switch whereby the latter is actuated. 105

2. In an electric circuit controller, the combination of a motor, two sets of terminals, one for the motor armature circuit and one for the field circuit, a shaft, connections between the motor and the shaft for revolving the latter, a lever loosely journaled between its ends on said shaft, means for normally holding the lever with its contacts in connection with the terminals during the greater part of the revolution of said shaft, and means connected with said shaft for releasing the lever at a period of the shaft's revolution, whereby the lever may turn and move the contacts first out of connection with the armature circuit terminals and then out of connection 115 with the field circuit terminals.

3. In an electric circuit controller, the combination of a motor, two sets of terminals, one for the motor armature circuit and one for the field circuit, a shaft, connections between 125 the motor and the shaft for revolving the latter, a lever loosely journaled between its ends on said shaft, means for normally holding the lever with its contacts in connection with the terminals during the greater part of 130

the revolution of said shaft, and means connected with said shaft for releasing the lever at a period of the shaft's revolution, whereby the lever may turn and move the contacts 5 first out of connection with the armature circuit terminals and then out of connection with the field circuit terminals.

In testimony whereof, I have signed my name to this specification, in the presence of two subscribing witnesses.

MAX SCHUPPE.
